UNITED STATES PATENT OFFICE

1,962,596

STORAGE FILE

Samuel C. Huffman, Lincoln, Nebr.

Application January 16, 1931, Serial No. 509,075

1 Claim. (Cl. 229—45)

My invention relates to storage files, its primary object being the provision of an exceedingly simple storage file which may be cheaply constructed and which may be sold at a low price.

Another of the objects of the invention is the provision of a storage file with a closure which effectively prevents the entrance of dust and of vermin.

10 It is also my object to provide a knock down storage file which may be quickly and easily set up for use.

It is also my object to provide a flexible strap which covers the narrow slit opening of the closure and to provide simple fastening means whereby the ends of the strap may be quickly and easily secured to the end walls of the storage file.

Having in view these objects and others which 20 will be pointed out in the following description, I will now refer to the drawing, in which

Figure 1 is a view in perspective of the storage file as it appears when partly closed.

Figure 2 is a perspective view of the storage 25 file as it appears when entirely closed.

Figure 3 is a sectional view through a portion of an end wall of the storage file and through the clip, showing particularly the manner in which the strap is held at its ends in fixed position.

Figure 4 is a view similar to Figure 3 but showing a somewhat modified form of clip.

The present invention contemplates the use of a storage file similar to those shown and described in my prior Patents No. 1,697,359 and No. 35 1,697,360, both granted to me on January 1, 1929. The present storage file itself is identical in all respects with those shown in my prior patents and the only difference is in the provision of a 40 simpler strap covering the slit in the meeting edges of the two top members which constitute the closure.

The blank from which the storage file is made is provided with end extensions 10 and with side 45 wall extensions 11 which constitute the closure. The end wall extensions are first bent down to partially close the top opening of the storage file and the side wall extensions 11 are then folded over the end wall extensions 10 to completely 50 close the top opening of the storage file. The combined width of the two side wall extensions 11 is equal to the width of the top opening of the storage file and the free edges of the side wall extensions 11 will therefore meet when they 55 are in their closing position. At the meeting

edges of the two side wall extensions there is a very narrow slit opening which would permit the entrance of dust and vermin to the interior of the storage file unless the slit were closed. It is also desirable to provide a latch which will 60 hold the two side wall extensions 11 in their closing position. All of this was done in the two prior patents above referred to.

In the present instance I employ a strap 12 of somewhat greater length than the length of the storage file and I secure this strap at the free edge of one of the side wall extensions 11. This strap may be made from fabric, leather, rubber, or any other suitable material of a similar nature. In some cases it may even be possible to use a 70 flexible metallic fabric. In any case the strap 12 should be thoroughly pliable and it should stretch very slightly under tension. It should be secured throughout half its width to a side wall extension 11 and it may be secured in any desired 75 manner as by means of an adhesive or by means of rivets or by any other suitable means.

The strap 12 is provided with a pair of apertures 13 in its opposite end portions. The end walls of the storage file are provided with hooks 14 for engaging the strap 12 through the apertures 13. In the Figure 3 construction this hook 14 is made by stamping out a piece of metal which is secured to the storage file. The metal is further provided with a plurality of apertures 85 which are made by punching the metal in a manner such that rivet portions 15 project rearwardly from the plate. This makes it an easy matter to secure the plates on the end walls of the storage file.

The fastener shown in Figure 4 differs from that in Figure 3 in that the plate is provided with a pivoted tongue 16 which offers considerable leverage in the stretching of the strap and in holding the strap in place.

When it is desired to close the storage file the flaps 10 are first turned inwardly into horizontal position after which the flaps 11 are folded down on the flaps 10 with the strap 12 completely covering the slit between the meeting edges of the flaps 11. The ends of the strap 12 are then grasped between the thumbs and forefingers and they are pulled down until the hooks 14 engage the strap 12 through the apertures 13. The only variation in the use of the Figure 4 modification 105 is that the tongues 16 are forced through the apertures 13 and they are then swung on their pivots in order to apply tension to the strap and to latch the strap in fixed position.

The important distinction between the present 110

construction and that disclosed in my Patent Number 1,697,359 resides in the nature of the material of which the strap 12 is formed. This strap is so pliable that it bends into a sharp angle under its own weight. It possesses sufficient elasticity so that it may be stretched taut over the seam between the cover members 11. The steel strap of my former construction is readily bendable into a sharp corner but it will not bend under its own weight nor can it resume its straight form without effort on the part of the user. It covers the seam in the storage file but it can not be stretched under the tension employed in closing the storage file. If it becomes buckled it can not be stretched to remove the irregularities. With the flexible strap 12, the normal stretching incident to its fastening will tighten it so that its lateral edges will both be in close contact with the cover member to form a perfect closure for the seam. These qualities are found only in such materials as webbing, rubber, leather and similar materials. It is to be understood therefore that where I use the term "strap" in the description and claims of the present application, that term refers only to straps made of a material which possesses the degree of resiliency, elasticity and flabbiness found in such materials as rubber, leather and fabric.

Having thus described my invention in such full, clear, and exact terms that its construction and operation will be readily understood by others skilled in the art to which it pertains, what I claim as new and desire to secure by Letters Patent of the United States is:

A storage file having an open top, a pair of closure members having a hinged relation with said storage file at opposite sides of the opening thereof, the combined area of said closure members being substantially equal to the area of the opening of said storage file, an elastic tension strap secured to one of said closure members to overlie the edge portion of the other of said closure members, said strap being pliable and readily bendable and having end portions projecting beyond the ends of said storage file and adapted to be grasped for tensioning over the meeting edges of said closure members, said strap being provided with apertures in the end portions thereof, and hooks projecting from the end walls of said storage file for engaging said strap through the apertures thereof and for maintaining said strap under tension.
